6354X Thomas Fullon of Newick Connecticut
Letters Patent

The Schedule referred to in these Letters Patent and making part of the same contains a description in the words of the said Thomas Fullon himself of his improvement in the machine called "Fullon's Rotary Pump."

Know all men by these presents that of Thomas Fullon of Newick in the County of New London and State of Connecticut have invented a new and useful improvement called "Fullon's Rotary Pump." The principle of which improvement may also be applied to clean and other purposes. & that the following is a full and exact description of the construction and operation of said improved machine, reference being had in the following Specification to drawings accompanying and marked

"Drawings No 1." Fig 1. represents an edge view of the pump attached vertically to a flange cccc bolts which fasten together the front and back casings u of the crank and handle. a.b. the packing box. c.d. the cap to the packing box. e.f. the arbor or shaft. m. the nut fastening the crank on the shaft or arbor. Fig 2. is a front view of the pump. b. is the inlet of water or other fluid a. the outlet o.o.o.o.o the bolts to confine the two parts of the case together. g. the crank m. the handle to the arbor of the shaft or arbor. m. the nut d. the cap to the packing Box m.d. to represent a projection on the outside of the pump either cast with the pump or attached permanently with screw to the outside & connected with part d. (fig. 3.) c. is a nut attached to a screw passing through this projection and connected with the moveable part d. (fig. 3.) Fig. 3. is a vertical section of the pump showing an inside view of one of the casings. u.g.2. show the outside front case or frame fastened to the back case by bolts o.o.o.o. b. the inlet of the fluid. a. the outlet. A.B.C. the lower surface of one of the casings of the Pump. D.D.D. are three valves or slides as represented in fig 4. D. p. a friction Roller by the axis K. (as fig 4). B.E.I.R. a rise or elevation from the lower surface B.E. R is a groove formed by the elevations so raised parts w.w.w and T.T.P. both equally raised from the part B.E.I.R. the first projection from the lower surface A.B.C. to the elevation B.K.L.R. is the greater width of the flanges or

Jan 28, 1831

projecting sides of the wheel are represented a. b. c. d. figs (left & right) and the d. containing a. v. w. and I.T.P. correspond with the cavity in the body of the wheel. B.B.D. fig 6. e. t. x. is a permanent frame attached to this case b. d. entering the chamber and guiding and rendering firm a sliding gag d. this is fastened in by a screw connected with a nut. e. and passing through the projection e. the whole t. d. e. x. forming a permanent bar or gag filling the spaces between the elevation L.R.E. E. and the case w. y. z. and between the chamber A.B.C. & the wheel.

Fig 4 represents a horizontal section of the Pump passing thru its centre and cutting the shaft in a cross. a. b. c. d. represent a section of the wheel. D represents a valve sliding in a mortise in the wheel as in fig 6. A also is a groove in the flanches of the wheel. f. f. f. f. f. f. the motion roller x. x. the axes a. v. w. y. the elevations corresponding with a. v. w. y. in fig 3. R.V. T.L.P. the elevation represented in fig 3. T.L.P. - E.E showing the grooves in fig 3. E.E.R. - C the chuck with the rabbet drawn to the centre. m. l. the stuffing box m. l. cap to the stuffing box q. the crank e. e. the nut H the shaft or arbor o. e. c. e. connecting the front and back owing. Fig 5. Represents the edge of the wheel standing vertically. If the shaft or arbor a. b. c. d. the flanches or projecting sides of the wheel. the spaces c. c. between a. b. & c. d. form with the case the chamber or space to transmit the water or other fluid. A the mortise cut thru the hollow part of the wheel to the shaft to receive the valve D in figs 3. & 4. Fig 6. represents one side of the wheel L.N.P. represents the outer side of the wheel corresponding in width with the space A.B.C. (fig 3.) into which it runs. B.B.D. the space between the outer side L.N.P. and the shaft H is depressed to the precise elevation of a. v. w. and T.L.P. above the surface A.B.C. A A A mortise cut into the wheel and thru it from side to side. also thru the part of the wheel at C.C. (in fig 6.) to receive the sliding valve D.D.D. in fig 3.

From the preceding description it will be seen that the wheel. and the parts of the front and back surfaces must correspond. and if they do so. the relative proportion of the parts may be varied without affecting the principle. The thickness of the flanches or chuck of the wheel may be varied. also the space in the periphery

of the wheel between the flanthes carrying at the same time the corresponding parts in the two casings, for it will be perceived that the elevation of the second surface E. E. I. R. above the lower surface A. B. C. as represented in fig 3. must always correspond with the thickness of the projecting sides or flanthes of the wheel, and that the elevation of the wheel I. I. N. P. in fig 6. will fill the space between this elevation and the outer surface, also that the space in the wheel E. B. D is of the same depth with the elevation A. A. R. I. T. P. fig. 3. above the lower surface A. B. C. so that it is necessary that this correspondence should take place between the parts. It will also be perceived that the flanthes of the periphery of the wheel with the outside casing form the chamber or space into which the water or other fluid is received and thro' which it is conducted to the outlet. The three valves each entirely fill this chamber and form a close joint. These valves it will be perceived play into the mortise groove represented in figs. 5. & 6. also into grooves in the flanthes and the motion of them is regulated by the friction rollers passing into the groove formed as in fig 3. by the parts A. A. R. and I. T. P. It will also be seen that on applying the stationary bar slope or gag L. d. e. r. c. ^{fig 3.} the valve is by the bent shape of the groove drawn entirely within the wheel towards its centre and expressing the bar passes out and again occupies the whole chamber. The part L. d. e. r. c. fig 3. which I designate as the bar slope or gag forms a close joint. The object of the two sides L. & R. is to regulate and render firm the part d. This part as by the continued friction of the wheel it would be worn away and render the joint loose has attached to it a screw connected with a head on the outside with which the centre piece of the bar or gag can be regulated at pleasure. The wheel and shaft when made of a metallic substance is one entire casting. What I claim as my invention and for which I wish a Patent is the peculiar construction of the wheel, the arrangement of the valves in the wheel, and the means by which the valves are drawn to the centre of the wheel by the wheel movement. I also claim the exclusive right to the application of these improvements, & the use of this improved machine, not only as a pump of any size and for any kind of fluids, but as an engine for the application of steam for propelling boats, or any other purpose.
